UNITED STATES PATENT OFFICE.

HARRY L. REA, OF JENKINTOWN, PENNSYLVANIA.

AWNNG-FRAME.

1,147,544.

Specification of Letters Patent. Patented July 20, 1915.

Application filed December 17, 1912, Serial No. 737,273. Renewed March 3, 1915. Serial No. 11,878.

To all whom it may concern:

Be it known that I, HARRY L. REA, a citizen of the United States, residing at Jenkintown, in the county of Montgomery and State of Pennsylvania, have invented 5 new and useful Improvements in Awning-Frames, of which the following is a specification.

This invention relates to awning frames 10 and one of the principal objects of the invention is to provide a simple and efficient structure of this class having a minimum number of fastening devices and constructed in such manner that it may be readily removed or taken down without getting out of 15 the window.

Further objects of this invention will appear as the following specific description is read in connection with the accompanying 20 drawing which forms a part of this application, and in which:—

Figure 1 is a perspective view of the device with the awning shown in dotted lines. Fig. 2 is a detail side elevation with parts 25 broken away. Fig. 3 is a detail sectional view on the line 3—3 of Fig. 1. Fig. 4 is a view in side elevation showing the awning lowered.

Referring more particularly to the drawing, 1 represents an ordinary window frame to the opposite sides of which are secured the supporting devices 2. These supporting devices are substantially U-shape in form having both of their legs 3 and 4 apertured to 35 receive the connecting bolts 5 and 6. The supporting devices are connected to the frame by an integral screw 7 which is adapted to thread into the frame as shown, said screws being formed on the exterior surface. 40 of the supporting devices 2 at a point medially of the length thereof and projecting rearwardly therefrom. Removably secured in the supporting devices by the bolts 5 is a U-shaped frame 8 whose upper end is held 45 in removable engagement with the frame by the screw hooks 9. A similar U-shaped frame 10 is secured in the supporting devices by the bolts 6 and is adapted to be arranged at right angles to the frame 8 or to lie par-

allel therewith. The awning 11 is connected 50 to the frames in the usual manner.

It will be noticed that when the upper portion of the frame 8 is in engagement with the screw hooks and its lower ends or terminals of its legs connected in the supporting 55 devices by the bolts 5 that the same cannot be raised or lowered. Also by disconnecting the bolts 5 and slightly elevating the frame 8 the same may be disengaged from the screw hooks. Then by removing the bolts 60 6 the entire awning may be taken down without compelling the operator to get out of the window. In putting up the awning the frame 8 is engaged with the screw hooks 65 9 and the terminals of its legs connected to the supporting devices by the bolts 5, the frame 10 then has its terminals secured in the supporting devices by the bolts 6. Any suitable means for raising and lowering the awning may be provided.

Referring to Fig. 4 it will be noted that the awning can be lowered at night and thus prevent the currents of air from coming into direct contact with the occupants of the room. When the awning is in this position 75 the upper frame 8 is supported against further movement by the pivot 6 of the frame 10, thereby holding the awning 11 taut between the frames.

What is claimed is:—

A device of the class described comprising 80 a pair of U-shaped supporting members having integral screws formed therewith and projecting rearwardly for detachably connecting said members to the front of the 85 window casing, a pair of U-shaped frames, a separate bolt for each terminal of said U-shaped frames for pivotally connecting the frames to said U-shaped supporting member, said bolts being arranged in the 90 same horizontal plane.

In testimony whereof I affix my signature in presence of two witnesses.

HARRY L. REA.
